CORDWOOD CRIB OR SIMILAR ARTICLE

Henry Hudson, Boston, and Marie A. Kenrick,
South Yarmouth, Mass.

Application September 29, 1955, Serial No. 38,152

Term of patent 14 years

(Cl. D55—1)

Fig. 1

Fig. 2

Fig. 3

Fig. 1 is a perspective view of a cordwood crib embodying our new design;

Fig. 2 is a side elevation thereof; and

Fig. 3 is an end elevation thereof.

We claim:

The ornamental design for a cordwood crib or similar article, substantially as shown.
